(57) **CLAIM**

The ornamental design for a heat gun with positioning stand therefor, as shown and described.

DESCRIPTION

FIG. 1 a perspective view of a heat gun with positioning stand therefor, showing my new design;

FIG. 2 is a plan view of the left side of the embodiment of FIG. 1;

FIG. 3 is a top plan view of the heat gun with positioning stand of the embodiment of FIGS. 1-2;

FIG. 4 is a plan view of the right side of the embodiment of FIGS. 1-3;

FIG. 5 is a plan view of the front of the embodiment of FIGS. 1-4;

FIG. 6 is a plan view of the rear of the embodiment of FIGS. 1-5;

FIG. 7 is a plan view of the bottom of the embodiment of FIGS. 1-6;

FIG. 8 is a plan view of the left side of the embodiment of FIGS. 1-7 but with the base of the positioning stand disposed in a generally central orientation; and,

FIG. 9 is a plan view of the left side of the embodiment of FIGS. 1-8 but with the base of the positioning stand disposed in the opposite end of the arm than is shown in FIG. 2.

The broken line portions of the drawings are for illustrative purposes only and form no part of the claimed design.

1 Claim, 5 Drawing Sheets
